[57] CLAIM

The ornamental design for a combined jacket and hood, as shown and described.

DESCRIPTION

FIG. 1 is a front elevational view of a combined jacket and hood showing my new design, the hood being hidden from view, and the broken lines showing legible indicia being for illustrative purposes only and forming no part of the claimed design;

FIG. 2 is a rear elevational view thereof;

FIG. 3 is a front elevational view thereof, the hood being shown extended, and the broken lines showing legible indicia being for illustrative purposes only, forming no part of the claimed design; and,

FIG. 4 is a rear elevational view of FIG. 3.

The broken lines shown throughout the views are understood to represent conventional stitching.

FIG. 2

FIG. 4

UNITED STATES PATENT AND TRADEMARK OFFICE
CERTIFICATE OF CORRECTION

PATENT NO. : Des. 338,773
